UNITED STATES PATENT OFFICE.

JAMES M. HARRISON, OF ROCHESTER, NEW YORK, ASSIGNOR TO WHEELER & WILSON MANUFACTURING CO., OF BRIDGEPORT, CONNECTICUT, A CORPORATION OF CONNECTICUT.

THREAD-TWISTING MACHINE.

SPECIFICATION forming part of Letters Patent No. 760,623, dated May 24, 1904.

Application filed October 29, 1903. Serial No. 179,066. (No model.)

To all whom it may concern:

Be it known that I, JAMES M. HARRISON, of Rochester, in the county of Monroe and State of New York, have invented certain new and useful Improvements in Thread-Twisting Machines; and I do hereby declare the following to be a full, clear, and exact description of the same, reference being had to the accompanying drawings, forming a part of this specification, and to the reference-numerals marked thereon.

The object of my present invention is to facilitate the operation of twisting yarns, threads, cords, and the like by performing such an operation by means of an implement especially adapted for the purpose instead of by hand, as heretofore practiced; and it consists in producing a device of this character that may be manipulated with convenience and which will run rapidly and smoothly in operation.

To these and other ends my invention consists in certain features of construction and arrangement to be hereinafter explained, the novel features being pointed out in the claims hereunto annexed.

In the accompanying drawings, Figure 1 is side elevation of a device embodying my invention, parts being in section; and Fig. 2 is a top plan view of the same.

In order that a more complete understanding may be had of my invention, reference will be had to the herein-shown embodiment thereof, wherein 1 designates the supporting-frame of the machine, having an upwardly-extending and forwardly-curved arm 2, carrying at its upper end a horizontally-disposed bearing 3 and directly beneath it the vertically-disposed bearing 4, the latter being arranged in alinement with the bearing 5, carried by the forwardly-extending arm 6 of the base of the frame. Journaled in the bearing 3 is the shaft 7, carrying at one end the driving-wheel 8 and at the opposite end the adjustable stop-collar 9, against which bears the helical spring 10 in such a manner as to exert a force tending to separate the collar and the washer 11, that is loosely mounted upon the

shaft 7 and arranged to bear against the end of the bearing 3, the effect of this separating action between said collar and washer tending to hold the driving-wheel against its driven wheel with a yielding pressure. The driving-wheel 8 is provided with an operating-handle 12, by means of which it may be rotated, and in an annular groove upon the periphery of this driving-wheel is fitted an inset friction-band 13, bearing under the action of the spring 10 upon the surface of the friction-wheel 14, mounted upon the shaft 15, journaled in the bearings 4 5, the relative dimensions of the wheels 8 and 14 being preferably such that the speed of rotation of the latter will be materially increased over that of the former.

Mounted upon the shaft 15 and rotating with the friction-wheel 14 is a belt-wheel 16, in the grooved periphery of which runs the belt 17, passing around the pulley 18 of comparatively smaller diameter and mounted fast upon the spindle 19, which latter is revolvably mounted in the spindle-support 20, and into the upper end of this spindle is removably fitted a hook 21, adapted to be held in position by the set-screw 22, such a construction enabling new hooks or hooks of different kinds to be substituted as desired. In order that undue slack may be eliminated from the belt, the spindle-support 20 is slidingly mounted in the slot 23, formed in the base of the machine in such a manner that the movement of the spindle-support within said slot will vary the distance between the belt-pulleys 16 and 18 to adjust the tension of the belt connecting them, a set-screw 24 being employed for retaining the spindle-bearing in its adjusted position, that side of the slot opposite the screw being undercut or dovetailed to receive a corresponding projecting portion upon the adjustable bearing to insure a firm and proper seating of the pulley 18 in relation to the pulley 16 at various adjustments of the bearing.

In manipulating a machine of the character above described the thread to be twisted may be doubled upon itself or otherwise folded, as desired, and attached to the hook of the spindle, while its free ends are held in one hand

of the operator, and with the other hand the driving-wheel is operated until the thread has been twisted to the desired degree, at which time the thread may be waxed or otherwise 5 treated and finally removed from the hook to be subsequently used for any desired purpose.

Such a device constructed in accordance with my invention is comparatively simple and inexpensive to manufacture, and when 10 employed for the purpose above described it may be operated with the utmost facility and convenience, as the axis of the revolving spindle extends in a line substantially parallel to the plane of rotation of the driving- 15 wheel, thereby enabling the latter to be operated by one hand of the operator while the other holds the thread extended in a direction substantially in line with the axis of rotation of the spindle. Such a device will also run 20 smoothly and noiselessly in operation, and as the embodiment herein described is very compact and provided with an improved driving mechanism that is especially adapted to a device of this character it will be seen that a 25 thread-twisting device is produced that renders it possible to simplify and facilitate the operation above described and to enable the operation to be completed in a small fraction of the time required in twisting the thread 30 by hand.

I claim as my invention—

1. A thread-twisting device comprising a frame having a slot therein, and a bearing slidingly fitted in said slot, having a revoluble spindle mounted therein, a thread-engaging hook having its shank axially centered in said spindle and removably held therein, an arm carried by said frame having a driving-wheel mounted thereon, and intermediate driving-wheels 35 mounted between the arm and frame and a belt connecting the intermediate wheels to the spindle for operating it.

2. A thread-twisting device comprising a frame having an arm carried thereby, a driving-wheel mounted on said arm and in frictional engagement with intermediate driving 40 mechanism embodying a wheel of smaller di-

ameter upon said frame, means for holding said wheel and a belt-wheel rotating with said smaller wheel, a spindle-bearing mounted on 50 said frame carrying a revoluble spindle provided with a pulley, a belt adapted to connect said belt-wheel and spindle-pulley, means for adjusting the relation between said spindle-pulley and belt-wheel, and a thread-engaging 55 hook carried by said spindle.

3. A thread-twisting machine comprising a frame having a slot formed therein provided with an undercut portion at one side thereof, of a spindle-bearing slidingly fitted in said slot 60 and having a projecting portion entering the undercut portion of the slot, and means for retaining said bearing in adjusted position, a spindle revolubly mounted in said bearing, a thread-engaging hook carried by the spindle, 65 a driving-wheel mounted on the frame and arranged to rotate in a plane substantially parallel to the axis of rotation of the hook, and intermediate devices driven by the driving-wheel and connected to the spindle by a belt 70 so arranged as to be tightened by the adjustment of the spindle-bearing.

4. A device of the character described comprising a base, a spindle revolubly mounted thereon and carrying a hook to engage the 75 thread to be twisted, a belt-wheel revolubly mounted on the base, a pulley of smaller diameter on the spindle connected to the belt-wheel, a friction-wheel connected to and revolving with the belt-wheel, and a driving-wheel provided with an operating-handle and having a friction-band in the periphery thereof arranged to bear upon said friction-wheel, a shaft upon which the driving-wheel is mounted, a stop-collar carried by said shaft, 80 and a spring interposed between said collar and a relatively stationary portion of the base, and arranged to maintain said driving-wheel in frictional engagement with the friction-wheel.

JAMES M. HARRISON.
